UNITED STATES PATENT OFFICE.

OTTIS R. BRINEY, OF PONTIAC, MICHIGAN.

GUIDE BUSHING.

Application filed June 14, 1922. Serial No. 568,326.

To all whom it may concern:

Be it known that I, OTTIS R. BRINEY, a citizen of the United States, residing at Pontiac, county of Oakland, and State of Michigan, have invented a new and useful Improvement in Guide Bushings, of which the following is a specification.

My invention relates to guide bushings which telescope into each other and lock to each other without additional mechanism.

The object of my invention is a means of guiding drills, reamers, or other tools in an efficient manner and provide this means with time and labor saving features.

I attain this object by the mechanism illustrated in the accompanying drawing which exemplifies the present invention in a guide bushing having one slip bushing and in which drawing Fig. 1 is a general side view 15 of a guide bushing partly broken away to show the mechanism clearly; Fig. 2 is a section on line 2—2 of Fig. 1 showing the bushings in locked position; and Fig. 3 in a sectional view similar to Fig. 2 but showing the 20 bushings in unlocked position.

Similar reference characters refer to similar parts throughout the views.

The present invention is an improvement over my application for United States 30 patent now known as Serial No. 450,935.

Guide bushings, as formerly made with a counterbore in the liner bushing and a head on the slip bushing which head entered the counterbore, have the disadvantage of chips 35 collecting in the counterbore when changing or, for other reasons, removing the slip bushing. It is a rather difficult and time consuming operation to properly clean the bottom of this counterbore so that the head 40 of the slip bushing can rest squarely on the bottom of the counterbore.

The present invention eliminates the seat of the head on the bottom of the counterbore and provides for such seat on the top of the 45 liner bushing where such seat can readily be cleaned and thereby save considerable time in operation.

Jigs and fixtures with guide bushings are 50 extensively used for rapid and accurate production of work and even a slight improvement on these jigs and bushings, to save time or produce better work, is a decided advance in the art and of benefit owing to the quantity of such bushings used.

Referring now particularly to the drawing which shows the liner bushing A and the slip bushing B therein.

The liner bushing A has the body portion 10, the head 11 concentric with the body portion, the central bore 12 concentric with the body portion, and the counterbore 13 eccentric with the body portion.

The wall of the counterbore 13 is inclined to the longitudinal axis of the bushing for the purpose hereinafter set forth.

The top 14 of the liner bushing should be square with the body portion.

The slip bushing B has the body portion 15, the main bore 16 concentric with the body portion, the head 17 concentric with the body portion, the counterbore 18 provided as a lubricant receptacle, and the collar 19 eccentric with the body portion.

As seen in Fig. 2, the body portions 10 and 15 are concentric with the center 20; the counterbore 13 is concentric with the center 21 but eccentric with the center 20; and the collar 19 is concentric with the center 22 but eccentric with the center 20.

It is noted that the length of the collar 19 is less than the depth of the counterbore 13 and that the outer circumferential surface of this collar is inclined to the longitudinal axis of the bushings and that this inclination corresponds to the inclination of the outer wall of the counterbore 13.

In order to insert or remove the slip bushing B, it is rotated until the centers 21 and 22 coincide as seen at 23 in Fig. 3. At this point, the collar 19 will readily slip into the counterbore 13.

In order to lock the bushings to each other, either of the bushings may be rotated in either direction, whereupon the eccentrics become opposed and the centers 20, 21, and 22 may assume the relation shown in Fig. 2, and both bushings are locked firmly to each other.

When the bushings are so rotated, the inclination of the wall of the counterbore 13 and the outer circumference of the collar also forces the liner bushing downward so that the under side of the head 17 rests firmly upon the end 14 of the liner bushing, but the lower end of the collar 19 does not engage the lower wall of the counterbore thus providing the space 24.

The end 14 can be cleaned readily when

2
the slip bushing is not in place and the bottom wall of the counterbore need not be cleaned thoroughly since the slip bushing does not rest thereon.

5 It will be seen that this invention provides a guide bushing which saves considerable time in changing slip bushings as is necessary when changing from drill to reamer in the same jig for instance, and eliminates 10 the former tedious operation of cleaning out the counterbore.

Furthermore, the structure shown here 15 prevents chips etc. from entering the counterbore and thereby eliminates collection of chips therein; whereas, in former construction, the chips could readily enter the open portion between the eccentric elements and collect there and clog the movement of the eccentric elements. All of which disadvantages are eliminated in the present invention.

20 I claim:

1. A guide bushing comprising, a liner bushing provided with an eccentric counterbore, and a slip bushing guided in said liner bushing, and provided with an eccentric collar disposed in said counterbore to engage the wall thereof by a rotative movement of said slip bushing and bind said slip bushing 25 by both sidewise and lateral pressure with a

space between the end of said eccentric collar and the bottom of said counterbore.

2. A guide bushing comprising, a liner bushing provided with an eccentric counterbore having an inclined circumferential 35 wall, and a slip bushing guided in said liner bushing and provided with an eccentric collar disposed in said counterbore and the outer circumference thereof inclined to engage said inclined wall by a rotative movement of said slip bushing and bind said slip bushing by both sidewise and lateral pressure with a space between the end of said eccentric collar and the bottom of said counterbore.

3. A guide bushing comprising, a liner bushing provided with an eccentric counterbore having an inclined circumferential wall, a slip bushing guided in said liner bushing and provided with a head and with an eccentric collar disposed in said counterbore and the outer circumference thereof inclined to engage said inclined wall by a rotative movement of said slip bushing and bind said head to said liner bushing by a lateral pressure and the body of said slip bushing to said liner bushing by a sidewise pressure with a space between the end of said eccentric collar and the bottom of said counterbore.

OTTIS R. BRINEY.
